UNITED STATES PATENT OFFICE.

GEORGE GROW, OF BOSTON, MASSACHUSETTS, ASSIGNOR TO GEORGE GROW TIRE COMPANY, OF BOSTON, MASSACHUSETTS.

DESIGN FOR A TIRE FOR MOTOR-VEHICLES.

59,418.

Specification for Design.

Patented Oct. 18, 1921.

Application filed May 10, 1921. Serial No 468,429. Term of patent 14 years.

To all whom it may concern:

Be it known that I, GEORGE GROW, a citizen of the United States, residing at Boston, in the county of Suffolk and State of Massachusetts, have invented a new, original, and ornamental Design for a Tire for Motor-Vehicles, of which the following is a specification, reference being had to the accompanying drawing, forming a part thereof.

Figure 1 is a sectional view of a tire showing my new design; and

Fig. 2 is a top plan view of same.

I claim:

The ornamental design for a tire for motor vehicles as shown.

GEORGE GROW.
